DES. 2077

Elmer J. Key of Lowell, Mass.
assignor to

The Lowell Manufacturing Company of the same place.

Letters Patent No. 2077-Dated May 30, 1866.

Design for a Carpet Pattern.

The schedule referred to in these Letters Patent and making part of the same.

To all whom it may concern:

Be it known that I, Elmer J. Key of Lowell, in the County of Middlesex and State of Massachusetts, have originated and designed a new pattern for carpets or other fabrics, of which the following is a full, clear and exact description, reference being had to the accompanying drawings, making part of this specification.

A in the centre is a group of leaves.

B. B. in the corners when matched will form a cross shaped figure with irregular outlines, said figure resting on the bar C. The border or side border is composed of blocks, the interior composed of fine regular work, as shown in the drawing.

E. E. are two quarters of a cross shaped figure, the particular shape of which is shown in the drawing and resting on bar F. F. Side bars are composed of small blocks.

Bars C and F running at right angles with each other, and when matched will form a large diamond. The rest of the space is occupied by small diamonds C. C. C. C.

The colors employed for the different portions of the design, may be varied to suit the taste and wish of the manufacturer.

Claim

What I claim as my invention and desire to secure by Letters Patent is The Design or Pattern for carpets or other fabrics herein set forth.
